UNITED STATES PATENT OFFICE.

ROBERT A. OGLE, OF CHICAGO, ILLINOIS.

WATER-CRANE.

No. 913,909.

Specification of Letters Patent.

Patented March 2, 1909.

Application filed June 19, 1908. Serial No. 439,283.

To all whom it may concern:

Be it known that I, ROBERT A. OGLE, a citizen of the United States, residing at Chicago, in the county of Cook and State of Illinois, have invented a new and useful Improvement in Water-Cranes, of which the following is a specification.

My invention relates, more particularly, to improvements in water-cranes of the variety employed in railway equipments for supplying water to locomotive-tenders; and some of my objects are to render the valve-mechanism of the crane easy of operation under high water pressure; to obviate any hammer effect of the water upon the parts of the valve when it is operated to close it; to produce slow turning of the valve in closing it; and to close the valve in such a manner as to fully apprise the operator of the operation of the valve.

Other important objects of my invention are to render the connection of the spout section with the vertical pipe section of the crane capable of turning in any desired direction without turning the vertical column; to render this connection of such a character that under continuous use wear of it will not cause it to become leaky, but on the other hand will cause it, by such use, to produce a better joint; and to provide a construction by which the end of the spout, in moving from inoperative to operative position, will travel in a curved path, and when so moving will be raised to automatically clear any obstacle in its path, and be finally deflected into the inlet of the tank to be filled.

My invention is illustrated in the accompanying drawings, in which—

Figure 1 is a broken view in elevation and partly in sectional elevation of the upper end of a water-crane constructed in accordance with my invention. Fig. 2 is a view in sectional elevation of the lower end of the water-crane illustrated in Fig. 1. Fig. 3 is a view in front elevation and partly in sectional elevation of the upper end of the water-crane illustrated in Fig. 1. Fig. 4 is a section taken at the line 4 on Fig. 3 and viewed in the direction of the arrow. Fig. 5 is a view in end elevation of the construction illustrated in Fig. 2. Fig. 6 is a section taken at the line 6 on Fig. 5 and viewed in the direction of the arrow. Fig. 7 is a section taken at the line 7 on Fig. 2 and viewed in the direction of the arrow; and Fig. 8, a

section taken at the line 8 on Fig. 2 and viewed in the direction of the arrow.

The lower end-portion or water-box of the crane is represented at 9 and, as shown, is formed with an elbow 10 at the end 11 of 60 which the water-main (not shown) through which water is supplied to the crane, may be attached, it being understood that this portion of the crane, as is commonly the practice, is located under ground. The vertical 65 pipe section 12 which extends upward about 14 feet above the level, is formed at its upper extremity with a tubular head 13, the upper open end of which is screw-threaded as indicated at 14 to receive a hollow bearing-head 70 15 of semi-spherical shape as represented, the upper marginal circular edge-portion of this head being provided with an inwardly extending annular flange 16 having a tapering upper surface 17 forming a track, for a 75 purpose hereinafter explained.

The spout which is represented at 18 is shown in part only, the portion shown being that which attaches to the vertical pipe 12. The portion of the spout illustrated is 80 formed in sections to afford a head of general spherical shape, the upper section 19 of which being of semi-spherical shape, and its lower section 20, which is bolted to the upper section as indicated at 21, being likewise of 85 general spherical shape, the inner surface of the section 20 being of a curvature corresponding with that of the outer surface of the head 15 about which this section 20 extends. The section 20 is provided with an annular 90 flange 22 about its periphery, the under side of which flange describes an ogee curve as represented and forms a track 23.

The head 13 is so formed as to provide two sets of diametrically disposed horizontal lugs 95 24, in the construction illustrated these lugs being so positioned as to extend approximately parallel with the spout 18 when the latter is in inoperative position. These sets of lugs form bearings for vertically disposed 100 rods 25 and 26 between washers 27 on which and the adjacent lower lugs, springs 28 are confined to normally hold the rods 25 and 26 in raised position. The rods 25 and 26 carry rollers 29 and 30, respectively, at their 105 upper extremities, these rollers being so positioned as to cause them to bear against the track 23, and the springs being so tensioned that the engagement of the rollers with the track will cause the section 20 to be 110

held in close contact with the bearing surface of the head 15, regardless of the position of the spout, and thus constantly insure a tight joint between the spout and the head 15.

5 The head 19 carries two opposed horizontal bosses 31 in which shafts 32 carrying rollers 33 on their inner ends are journaled, these rollers having beveled roller-surfaces, as indicated at 34, which roll upon the 10 beveled track 17, as represented in Fig. 3, for a purpose hereinafter explained.

The track 23 is of such a curvature that the spout 18, when it is in the position relative to the rollers 29 and 30 illustrated in 15 Fig. 1, and extends parallel with the track (not shown) along side of which it is stationed, inclines upwardly, in which position it is locked against accidental turning, as for instance when the wind is high, by engagement 20 of its roller 29 with a depression 35 formed in the track 23. In this position of the spout the rollers 33 extend at right angles to the rollers 29 and 30, as clearly represented in Fig. 3. As the spout is swung 25 about its connection with the head 13 to operative position at a right angle to the railway track, it is caused, by the curvature of the track 23, to move in a curved path, the outer end of the spout gradually rising 30 during the initial portion of its movement by reason of the rolling engagement of the roller 29 upon a cam-surface 36 of the track, and descending throughout the remainder of its movement as the roller 29 traverses an inclined 35 surface 37 of the track, the curvature of this track being such that by the time the spout has moved to a position in which it extends at a right angle to the railway track, the rollers 29 and 30 rest at portions of the 40 track, one of which is represented at 38, which are located in the same horizontal plane. Thus when the spout is moved into operative position, the rollers 33 extend immediately above the rollers 29 and 30, and 45 the spout, by reason of its weight and the change of the fulcrum point on account of these rollers moving from a position at right-angles to each other to a position in which they are superposed, which results by so 50 operating the spout, descends at its outer ends, in which lowered position it is intended that the water be supplied through the crane to the locomotive-tender.

The description of the valve-mechanism 55 for controlling the flow of water through the crane is as follows: The elbow 10 at its junction with the vertical portion of the crane contains an annular inwardly extending flange 39 disposed at right angles to the 60 wall of the elbow. A hollow frusto-conical casing 40 having a closed end 41, an open end 42, and a circular wall 43, is secured to the flange 39 at a rim 44 on the casing 40, through the medium of bolts 45, the wall 65 43 of the casing, which is thus spaced through-

out its extent from the wall of the elbow, containing equidistantly spaced ports 46. Rotatably confined in the casing 40 to fit its tapering inner surface is a hollow plug 47, open at both ends and having ports 48 in its 70 wall spaced apart from each other in the same manner as the ports 46 are separated. The interior of the plug contains two spaced transversely extending spider-frames 49 and 50, the frame 50 having a boss 51 containing an opening 52 through it concentric with the wall of the plug 47, in which opening a hollow shank 53 is keyed to render it movable with the plug 47. The outer end of the shank 53, which is recessed as indicated 80 at 54, is journaled in an opening 55 in the wall of the vertical pipe 12. A sleeve 56 is fixed on the shank 53, and extending from this sleeve is a crank-arm 57 to which a valve-operating rod 58 is secured, it being 85 preferred that this rod be formed in sections 59 and 60 adjustable with relation to each other, as represented in Fig. 7. Thus by moving the rod up and down, as hereinafter described, the plug 47 is caused to be turned 90 in opposite directions in the casing 40 to cause the ports 48 in the plug to be moved into and out of registration with the ports 46 in the wall 43 for controlling the flow of water through the crane. 95

In the construction illustrated, the valve-actuating rod 58 which extends upwardly through the center of the vertical pipe 12 is bifurcated at its upper end as indicated at 61, at a point approximating the center of the 100 spherical heads 15 and 19, the rod 58 being provided near its upper end with a universal joint 62. Pivoted to the bifurcated upper end of the rod 58, as indicated at 63, and extending rearwardly, is an arm 64 which is 105 fixed on a shaft 65 journaled in bearings 66 provided on the head 19, the ends of this shaft extending beyond the bearings 66 as indicated in Fig. 4. An operating lever 67 having a bifurcated portion affording arms 110 68 is attached at these arms to the outer ends of the shaft 65, as clearly illustrated in Fig. 4, this lever extending above the spout and substantially parallel with it. The lever 67 at its connections with the shaft 65 115 has a yoke-extension 69 which preferably extends approximately in the same plane with the arm 64, and carries at a stem 70 thereon an adjustable weight 71 tending normally to turn the shaft 65 in its bearings 120 to raise the levers 67 and 64 and rod 58, the rotary plug 47 being so positioned with relation to the rod 58 as to cause the ports 48 in the plug to be out of registration with the ports 46 in the casing 40 when the lever 67 125 and rod 58 are in their normal positions as represented in Fig. 1.

The operation of the apparatus as described is as follows: The normal inoperative position of the crane is that illustrated in 130

Figs. 1, 2 and 3 in which the roller 30 engages with a low portion of the track 23 and the roller 29 rests in the recessed portion 35 thereof, thereby causing the spout to incline 5 upwardly, it being intended that the crane be so positioned along side of a railway track that when its spout is positioned as just described it will extend parallel with the railway track and be normally out of the way of 10 passing trains. When the parts are so positioned it will be noted that the head 20 is held in engagement with the outer semi-spherical surface of the head 15 by the engagement of the spring-supported rollers 29 15 and 30 with the track 23, and that the spout 18 is prevented from tilting side wise by the engagement of the rollers 33 with the track 17. In this normal position of the apparatus, the lever 67 and rod 58 are raised and the 20 ports 48 in the valve-plug 47 are out of registration with the ports 46 in the casing-wall 43, communication of the passage in the elbow 10 with the passage in the remainder of the structure being closed. When it is desired 25 to operate the crane to supply water to a locomotive tender, for example, on a railway track beside the crane, the operator grasps the spout and swings it from its normal position described to a position in which 30 it extends at a right angle to the railway track. In so swinging the spout, it turns at its spherical bearing connection with the head 15, the track 23 moving in contact with the rollers 29 and 30, causing the outer 35 end of the spout 18 to move in a curved path, first rising by reason of the cam-surface 36 and then gradually descending as the inclined portion 37 of the track rides on the roller 29, the curvature of this track, as before described, being such as to permit the outer 40 discharge end of the spout to descend into the inlet of the tender. In this position of the spout the rollers 33 are above the rollers 29 and 30, and the spout 18 is thus free to 45 drop by gravity to the downwardly inclined discharge position. With the spout in operative position, the operator then pulls down the lever 67 thereby rocking the shaft 65 and lowering the rod 58 against 50 the resistance of the weight 71. By lowering the rod 58, the plug 47 is turned in the casing 40 to cause its ports 48 to register with the ports 46 in the casing-wall 43, and the water entering the elbow 10 from the 55 water-main connected with it, freely passes through the valve and vertical pipe section 12 and out at the discharge end of the spout. It will be noted that the effect of the water pressure against the head 19 of the spout 60 tends to lift the latter, thereby relieving the pressure of the head 19 on the springs 28 and by such lifting action tending to force the semi-spherical head 20 into closer bearing contact with the correspondingly-shaped 65 bearing-surface of the head 15. The effect

of this action is to cause an absolutely water-tight connection to be afforded, the tendency being to cause this connection to be rendered more and more perfect as the use of the apparatus continues. When it is desired to 70 arrest the flow of water through the crane, the operator releases the lever 67, whereupon the latter swings to normally raised position under the action of the weight 71 and draws the rod 58 upward, with the result of causing 75 the ports 48 in the plug 47 to be moved out of registration with the ports 46 in the casing-wall 43, thereby closing communication between the elbow 10 and the vertical pipe 12. To avoid too rapid ascending of the rod 58 80 and the consequent rapid turning of the plug 47 when the lever 67 is released as described, I provide a cushioning device, of which the following is a description: The recessed end 54 of the shank 53 extends beyond the wall of the pipe 12 and has fixed on it a sleeve 72, this sleeve having a crank-extension 73 connected to the piston 74 of a dash-pot 75 of ordinary construction, through the medium of a link 76. The 90 dash-pot contains two openings 77 and 78 in its rear wall 79 communicating with the interior of the pipe 12, the opening 78 being controlled by a needle-valve 80. The walls of the dash-pot contain a third opening 81, 95 this opening being located in its outer wall a slight distance above the opening 77. The piston 74 is of a size and the openings 77 and 81 are so located as to render communication between the interior of the pipe 12 and the opening 81 closed when the piston is in the raised position illustrated in Fig. 6, and to cause communication to be open between the opening 81 and the interior of the pipe 12 when the piston is at the limit of its downward stroke. The position occupied by the piston 74, when the rod 58 is down and water is discharging through the crane, is that illustrated in Fig. 6. Thus when the operator releases the lever 67 and the rod 58 100 starts to move upward, as before described, its speed of movement is regulated by the speed of movement of the piston 74 in forcing the water from the dash-pot out of the opening 78, and the rod may thus be caused 105 to turn the valve as slowly as desired to obviate water-hammer.

I preferably so construct the rotary valve mechanism as to cause the plug 47 to be moved slightly in a longitudinal direction 110 to effect close engagement with the inner surface of the casing-wall 43, when the rod 58 is actuated to close this valve; and to withdraw it slightly when the rod is actuated to open the valve, this result being accomplished by the following-described construction: The outer end of the shank 53, which is of circular shape in cross-section, carries a thread 82 which screws on to a threaded boss 83 on a plate 84 adjustably secured, as 115 120 125 130

by bolts 85, to the wall 86 of the pipe 12, in line with the shank 53. The threads of this threaded connection of the shank 53 with the plate 84 are so disposed as to cause the shank to partially unscrew from the boss 83 when the rod 58 is moving downward as described, and thus the plug 47 is forced at its outer tapered surface into intimate contact with the inner surface of the casing-wall 43; 10 and to cause the shank 53 to screw upon the boss 83 when the rod 58 is lowered, this feature of the construction insuring a tight valve joint and at the same time preventing the binding or sticking of the valve. As supplementary means for preventing any hammer blow of the water upon the parts of the construction when it is shut off, I provide a valve, comprising a head 87 normally seating in an opening 88 in the closed end 20 41 of the casing 40, under the influence of a spring 89 surrounding the outer end of a valve-stem 90 carrying the head 87, and confined in the recess 54 in the shank 53, to bear against a washer 91 on the stem, and 25 a plate 92 bearing against an adjusting screw 93 in the plate. The spring 89 is so tensioned that the pressure of the water as it flows from the elbow 10 to the pipe 12 will not unseat the valve 87, but will do so 30 should the water be shut off suddenly enough to produce a water hammer.

By providing the before-described connection between the spout 18 and the pipe 12, the use of objectionable cup-leathers, or 35 the like devices, are avoided, and the joint thus formed instead of being liable to impairment from use, becomes more perfect as the use of the apparatus continues.

By constructing the rotary valve in accordance with my invention, it is rendered 40 completely balanced, permitting it to be turned in either direction with great ease regardless of the water pressure employed.

Another important feature of my invention is that of so constructing the lever mechanism as described as to permit the operator, by observing the lever 67 after he has released it, to know whether or not the valve controlling the flow of water through the 45 crane is being turned to shut off the water, as in doing so in the described construction the lever 67 must rise. Thus the liability of successive operations of the lever mechanism by the operator in order that he may 50 be certain of the shutting off of the valve, and consequent flooding of the ground about the crane, is avoided.

What I claim as new, and desire to secure by Letters Patent, is—

60 1. In a water-crane, a valve for controlling the passage of water therethrough, comprising a hollow casing provided in its wall with opposed ports and so positioned in the crane as to cause its port-equipped wall to 65 be spaced from the wall of the passage con-

taining it, a hollow plug rotatably confined in the casing and containing ports adapted to register with the ports of the casing, and means for rotating the plug in the casing.

2. In a water-crane, a valve for controlling 70 the passage of water therethrough, comprising a hollow casing having a closed end-wall extending at substantially right angles to the course of the water through the passage in which the valve is located, another 75 wall of said casing extending longitudinally of the passage-wall and spaced from it and containing opposed ports, a hollow plug rotatably confined in the casing and containing ports adapted to register with the 80 ports in the casing, and means for rotating the plug in the casing.

3. In a water-crane, the combination of an 85 annular flange on the inner surface of the passage-wall of the crane, a valve for controlling the passage of water through the crane, comprising a casing secured to said flange in position to cause the wall thereof containing opposed ports to be spaced from the wall of the passage in which the valve 90 is located, a hollow plug rotatably mounted in the casing and having ports adapted to register with the ports in the casing, and means for rotating the plug.

4. In a water-crane, the combination with 95 an upright pipe and a second pipe extending at an angle thereto, of a valve for controlling the flow of water from the said second pipe to the vertical pipe, comprising a casing and provided with ports in a wall thereof, said 100 port-equipped wall extending longitudinally of the said second pipe, a hollow plug rotatably confined in the casing and provided with ports adapted to register with the ports in the casing, a shank connected with said 105 rotary plug, and means for turning the shank to turn the plug in the casing.

5. In a water-crane, the combination of a 110 valve for controlling the passage of water therethrough provided with a wall extending at approximately right angles to the course of the water through the crane at the point at which the valve is located, said wall having an opening through it, and a spring-tension valve operating to open and close the 115 opening in said wall, for the purpose set forth.

6. In a water-crane, the combination of a 120 valve for controlling the passage of water therethrough, comprising a casing provided with an end wall extending at approximately right angles to the course of the water through the crane at the point at which the valve is located, and opposed ports in the 125 casing, a hollow plug rotatably confined in the casing and containing ports adapted to register with the ports in the casing, said end wall being provided with an opening through it, and a spring-pressed valve for controlling the passage of water through the opening in said end wall, for the purpose set forth. 130

7. In a water-crane, a valve for controlling the passage of water therethrough, comprising a hollow casing of frusto-conical shape having a wall thereof spaced from the wall of the passage at the point where the valve is located and containing opposed ports, a hollow tapering plug rotatably confined in the casing and containing ports adapted to register with the ports in the casing, a shank connected with the plug, and means for causing the plug to be moved longitudinally of the casing in opposite directions as the valve is operated to open and close, for the purpose set forth. 65
- 10 8. In a water-crane, the combination with its vertical pipe-section and a second pipe extending at an angle to said vertical pipe-section, of a valve for controlling the flow of water from said last-named pipe to the vertical pipe comprising a casing having a wall thereof spaced from the wall of the passage at the point where the valve is located and containing opposed ports, a hollow plug rotatably confined in the casing and provided 70 with ports adapted to register with the ports in the casing, and a shank connecting with the plug and extending beyond it, a rod extending through the vertical pipe-section and connected with said shank in a manner to permit the valve to be rotated by operating the rod, and means for raising and lowering said rod, for the purpose set forth. 75
- 15 9. In a water-crane, the combination of a rotary valve for controlling the passage of water through the crane, a shank connected with the valve for operating it, a valve-actuating rod constructed and arranged to turn the shank to open and close the valve and tending to normally maintain the valve 80 in closed condition, and cushioning means connected with the shank for retarding the movement of the shank inclosing the valve. 85
- 20 10. In a water-crane, the combination of a valve for controlling the passage of water through the crane, comprising a casing of frusto-conical shape having a wall thereof spaced from the wall of the passage at the point where the valve is located and containing opposed ports, a hollow tapering plug rotatably confined in the casing, a shank extending from said plug and suitably journaled near its outer end, and means for moving the shank lengthwise to effect adjustment of the plug in the casing, for the purpose set forth. 90
- 25 11. In a water-crane, the combination of an upright pipe-section provided at its upper end with a semi-spherical bearing-head, a spout-section carrying a semi-spherical head embracing the head on said pipe-section, said last-named spherical head being so disposed as to cause it to tend to drop by gravity out of engagement with said bearing-head, and means for holding said last-named 95 head in close engagement with the bearing-head, for the purpose set forth. 100
- 30 12. In a water-crane, the combination with its upright pipe-section surmounted by a semi-spherical bearing-head, of a spout formed with an elbow the depending portion 70 of which terminates in a semi-spherical head embracing said first-named head, for the purpose set forth. 105
- 35 13. In a water-crane, the combination with its vertical pipe-section provided with a semi-spherical bearing-head at its upper end, of a spout joined to said pipe-section and formed with a semi-spherical head embracing said first-named head, and means for holding the head on the spout in close engagement with the head on the vertical pipe-section, for the purpose set forth. 110
- 40 14. In a water-crane, the combination with its vertical pipe-section provided with a semi-spherical bearing-head on its upper end, 85 of a spout joined to said pipe-section and formed with a semi-spherical head adapted to embrace the head on the vertical pipe-section, and roller-mechanism constructed and arranged to support the spout at its 90 head upon the vertical pipe-section, for the purpose set forth. 115
- 45 15. In a water-crane, the combination with its vertical pipe-section and a spout-section connected with said pipe-section in a 95 manner to permit the spout-section to be swung about said pipe-section as a pivot and be raised and lowered at its outer end during such swinging movement, of a track carried by one of said sections, and means on the 100 other of said sections engaging with the track, for the purpose set forth. 120
- 50 16. In a water-crane, the combination with its vertical pipe-section and a spout connected with said pipe-section in a manner 105 to permit the spout to be swung about said pipe-section as a pivot and be raised and lowered at its outer end during such swinging movement, of a track of irregular shape 110 carried by the spout, and means on the crane 115 upon which the head bears at its track during the swinging of the spout. 125
- 55 17. In a water-crane, the combination with its vertical pipe-section and a spout connected with said section in a manner to 115 permit the spout to be swung about said pipe-section as a pivot and be raised and lowered at its outer end during such swinging movement, of roller-mechanism supported on the crane, and a track of irregular form 120 carried by the spout, at which track the spout is adapted to bear on the roller-mechanism, for the purpose set forth. 125
- 60 18. In a water-crane, the combination with its vertical pipe-section and a spout connected with said section in a manner to 125 permit the spout to be swung about said pipe-section as a pivot and be raised and

lowered at its outer end during such swinging movement, of spring-pressed rollers supported on the crane, and a track of irregular form carried by the spout, at which track the 5 spout is adapted to bear on the roller-mechanism, for the purpose set forth.

19. In a water-crane, the combination with its vertical pipe-section and a spout connected with said pipe-section in a manner 10 to permit the spout to be swung about said pipe-section as a pivot and be raised and lowered at its outer end during such swinging movement, of a track of ogee form carried by the spout, and means on the crane engaging 15 with the track, said track being of a form adapting the spout to move in an upwardly curved path when turned at its connection with the vertical pipe-section.

20. In a water-crane, the combination with its vertical pipe-section, provided near 20 its upper end with a hollow semi-spherical head, of a spout formed with a semi-spherical head embracing the semi-spherical head on the upper end of the vertical pipe-section, 25 means at opposite sides of the crane for supporting the spout at its head to hold it in engagement with the head on the vertical pipe, and means carried by the head on the spout engaging with the head on the vertical 30 pipe-section for insuring the alinement of the spout.

21. In a water-crane, the combination with its vertical pipe-section, provided near 35 its upper end with a hollow semi-spherical head, of a spout formed with a semi-spherical head embracing the semi-spherical head on the upper end of the vertical pipe-section, means at opposite sides of the crane for supporting the spout at its head to hold it in engagement with the head on the vertical pipe, and rollers carried on the inside of the head of the spout and bearing against the upper 40 circular edge-portion of the head on the vertical pipe section, for the purpose set forth.

45 22. In a water-crane, the combination with its vertical pipe-section and valve mechanism for controlling the passage of water through the crane, of a spout-section having ball-and-socket connection with the upper 50 end of the vertical pipe-section, a rod extending upward through the vertical pipe section connected near its lower end with the valve to operate it when the rod is moved up and down, an operating lever pivoted to the 55 spout, and a connecting arm extending from said lever and pivoted to the upper end of said rod at a point approximately coincident with the center of the circle described by the

bearing surfaces of the members of the ball-and-socket joint. 60

23. In a water-crane, the combination with its vertical pipe-section and valve mechanism for controlling the passage of water through the crane, of a spout-section having ball-and-socket connection with the upper 65 end of the vertical pipe-section, a rod extending upward through the vertical pipe-section connected near its lower end with the valve to operate it when the rod is moved up and down, an operating lever pivoted to the 70 spout, a connecting arm extending from said lever and pivoted to the upper end of said rod at a point approximately coincident with the center of the circle described by the bearing surfaces of the members of the ball-and-75 socket joint, and an arm-extension connected with the operating lever and carrying a weight, for the purpose set forth.

24. In a water-crane, the combination with its vertical pipe-section and a spout connected with said pipe-section in a manner to permit the spout to be swung about said pipe-section as a pivot and be raised and lowered at its outer end during such swinging movement, of a track of irregular shape constructed 80 and arranged to be movable with the spout, relatively stationary means bearing against said track at diametrically opposed points, whereby when the spout is swung from a position in which it parallels said means to a 85 position at right-angles thereto, the fulcrum point of the spout changes, for the purpose set forth.

25. In a water-crane, the combination with its vertical pipe-section and a spout connected with said pipe-section in a manner to permit the spout to be swung about said pipe-section as a pivot and be raised and lowered at its outer end during such swinging movement, of a track of irregular shape constructed 90 and arranged to be movable with the spout, relatively stationary means bearing against said track at diametrically opposed points, said spout being so constructed 95 as to cause the weight thereof to be approximately the same on opposite sides of its fulcrum point when the spout parallels said means and so constructed as to cause a greater weight to be produced on one side than the other of its fulcrum when the spout is 100 turned to a position at right-angles to said means. 105

ROBERT A. OGLE.
